(57) **CLAIM**

The ornamental design for a paper towel holder, as shown and described.

DESCRIPTION

FIG. 1 is a front, left and top perspective view of a paper towel holder, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the paper towel holder that form no part of the claimed design.
